UNITED STATES PATENT OFFICE.

EDWARD WYLDE, DECEASED, LATE OF NEW YORK, N. Y.; BY ELIZABETH WHITE WYLDE, OF NEW YORK, N. Y., AND NEW YORK TRUST COMPANY, EXECUTORS.

MECHANISM FOR CONTROLLING ELEVATORS.

Application filed April 18, 1921. Serial No. 462,195.

To all whom it may concern:

Be it known that EDWARD WYLDE, deceased, formerly a citizen of the United States, and residing at New York, N. Y., did, before his death, invent certain new and useful Improvements in Mechanism for Controlling Elevators, of which the following is a specification.

The object of the present invention is to provide mechanism by which an elevator despatcher located at a point remote from a bank of elevators may control or operate the same and receive at his station suitable automatic indications of the location of the cars and of the condition of the gates along the hatchway in which those cars are located.

In the operation of elevators it has been the custom before this invention to provide an operator on each car. In the case of heavy duty freight elevators, an operator permanently assigned to the car may not be necessary, but in such case it has been the custom for the employee using the elevator to operate the car himself. This is quite objectionable for many reasons and serious accidents have resulted from this method. In the case of a bank of elevators, for example in a warehouse where trucks are driven onto and off the elevator, shaft gates, often heavy fire doors, are provided. In such installations where there are several elevators, it is particularly desirable that the control of the elevators and gates shall be taken away from the workmen and located at a central despatcher's station, who shall control all of the cars of the bank of elevators. One object of my invention is to provide for a bank of so-called "operatorless" elevators. Obviously the despatcher, located perhaps at a distance from the cars, must have some indication of the condition of the gates of the bank and of the positions of the cars. The present invention accomplishes the above objects and provides a construction by which a single despatcher located at a distance from the bank of cars may control the same without having them even in sight.

The cars of the bank may be operated in various ways. A desirable form of construction is the so-called "push-button" type of elevator in which the operator needs merely to press a button corresponding to a floor to which the car is desired to be

sent and the car then automatically travels to and stops at that floor. It is also desirable that the gate at that floor then automatically open. This type of elevator is the one which is preferable, but it is obvious that the invention here under consideration is not necessarily limited to this type. It, however, has been thought advisable to indicate the present invention as applicable to this character of elevator, for that at present seems to be the more desirable construction.

Push button types of elevators are well known and it is not thought necessary to indicate specifically any such construction. One such is now in use in the United States in the so-called Army base in Brooklyn, New York, and is set forth and described in a pending application, Serial Number 446,120. In the drawings of the present application we have shown a portion of that construction, sufficient, it is believed, for a complete understanding of the present invention.

In the drawings showing the preferred embodiment of the present invention—

Figure 1 is a diagrammatic view of an elevator hatchway provided with three gates;

Figs. 2 and 3 are partial sections through two gates;

Fig. 4 is a diagram of connections;

Fig. 5 is a detail indicating the position of the "knock-outs" when a gate is fully open;

Fig. 6 is a simplified diagram of connections; and

Fig. 7 is a diagram of the despatcher's control panel for three elevators.

It is assumed that all of the cars and their associated gates and operating mechanisms may be alike. Referring to Fig. 1, this represents a hatchway having three floors, each provided with a heavy fire door gate 102, 103, 104, one at each floor. The car, not shown, may be attached to the hoisting cable 2, passing over a hoisting drum 3 driven by a hoisting motor, not shown, but shown at 2^a in Fig. 6 controlled by a switch 3^a. The gates may be operated in various ways, but I have shown them as operated independently from a common gate motor 105 which drives an endless chain 107. This may be clutched in any suitable manner to any one of the gate-operating sheaves 109 which then elevate the gate through suitable 110

cables 110 and 111, for example. Referring now to Fig. 2, the gate 103 is shown in its closed position. When the solenoid 122 is energized, it throws in the clutch 121 and 5 clutches the shaft of the gate drum 109 to the friction sprocket 120, which has its teeth in engagement with the driving chain 107. The gate will therefore rise and offset as indicated in Fig. 3 and will pass up 10 by the sill and door of the floor above. 125 is a cable which is operated by each of the gates as the gate rises, and which serves to connect that gate to a common gate-movement-controlling mechanism located, for example, at the top of the hatchway. In the 15 present embodiment, the cable 125 rotates the shaft 124 which in turn through the belt 130 rotates the "knock-out" shaft 132 on which are located the so-called "knock-outs" 133 to 139 and K, as indicated in Figs. 4 and 5.

In the present embodiment, when the car slows down to stop, for example when the power to the main hoisting motor is cut off, 25 a switch 38 closes, and the gate in the hatchway of that car and corresponding to the position of the car will automatically open.

Referring to Fig. 4, there is provided at 30 each gate a clutch 122, 220 or 223, one for each gate, each of which connects in its gate at the proper times. A common pair of gate-opening or gate-closing magnets 153 and 154 are provided which close and open certain switches at the proper times. A gate 35 selector is indicated by moving and stationary contact blocks designated as a whole by 145 which has a feed strip 147 and stationary blocks 231, 226 and 228 corresponding to the first floor, 230, 227 and 229 corresponding to the second floor, and 200, 219 and 164 corresponding to the third floor, together with a moving brush 146 moved correspondingly with the car. There is also 40 a solenoid magnet 156 energized at the proper time to make other connections.

Refer now to Fig. 6, which shows the 45 position of the parts when a car is at the first floor and with all its actuated gates closed, but before the car has moved away from the floor. Assume now that the despatcher desires to send that car to the third floor. He presses his button P. b. 3 (Fig. 7) corresponding to the third floor, the car will start, and move up toward the 50 third floor. The brushes 146 and A will move in the direction indicated by the arrows and leave their stationary contact blocks 228 and B. As soon as brush 146 moves off that block, it deenergizes the solenoid 156, which then drops to the position indicated by dotted lines. The switch 38 will have been opened by the solenoid 11 as soon as the power has been turned on to the hoisting motor, and will not re-close 55 until the car has slowed down to stop at the

third floor. When this happens, a circuit may be traced through switch 38, switch arm 161, solenoid 153, point 165, contact locks 162 and 163 (then closed by N), and out by way of block 164 and the moving 70 brush and feed strip 147. This will raise the core of solenoid 153 and close the switches 166 and 169. Solenoid 149 (Fig. 4) meanwhile is energized to lift the brake 148 from the motor. Energization of solenoid 75 153 has meanwhile closed switch 191 which thus energizes the third floor magnet 122, clutching that gate to the motor 105 and causing the gate to open automatically. Solenoid 156 has meanwhile been energized 80 through switch 169 and switch portion 177. It is thereafter maintained closed by the feed through resistance 230 and switch 178, which is closed by the rising of the core of solenoid 156. The gate continues to rise 85 until "knock-out" 137 opens its switch 161 as indicated in Fig. 5, thus deenergizing solenoid 153 and stopping the gate, where it remains locked through clutch 122 and the brake 148 on motor 105 which has then 90 been released.

The gate may then be closed if desired, by depressing the "close" button 195 in the 95 car or the similar "close" button 218 outside the shaft.

When such a push button elevator is provided, the despatcher may therefore, by pressing the button corresponding to the floor desired, send the car to that floor where it will stop and that gate only will automatically open. It may thereafter be closed, stopped, re-opened and handled as desired by the "open" or "close" buttons in the car or outside the shaft at that floor.

In order to control a bank of such elevators and gates, there is provided a central despatcher's station which may be located at any distance desired from the bank. Each of the elevators may be of the same construction and operation. In Fig. 7, for 110 example, is shown the panel board of the despatcher at his station, the three cars being indicated, with their control buttons P. b. 1, P. b. 2 and P. b. 3 for despatching 115 the cars as desired.

The despatcher, of course, should not start his car until the gate is closed. In order to indicate to him when this occurs, there has been provided signaling means which preferably indicates only when all the gates of 120 that shaft are shut. This may be in the form of a lamp I. The despatcher should also know where each of his cars is in the hatchways. This may be indicated to him by a row of lamps F, G, H, corresponding to the floors. In the present embodiment, these signal lamps may be connected, as shown in Figs. 4 and 6, and the gate lamp I is connected to the switch L held closed by the "knock-out" K so long as all the gates 125 130

- are shut, and which will release the spring pressed lever L to open the circuit when any gate starts to move. It is preferable that the position-indicating lamps shall be lighted only when the car is at rest or substantially at rest at a floor. This may be done by connecting them in parallel to contact blocks B, C and D corresponding to the similar floors, over which moves the brush 5
- 10 A and by connecting the return lead to the stationary contact blocks of switch P, N, O associated with the solenoid 156, which is one form of a mechanism for preventing the lamp selector from closing the circuits until the car has arrived at the floor desired 15 and the solenoid 156, a part of the gate-operating mechanism, has been energized.
- Now assume that car one is at the lower 20 floor with the gates of that hatchway all shut. The gate lamp I burns. The position lamp F is also lighted as its circuit is closed through the switch P, N, O, the solenoid 156 still remaining energized so long as brush 146 of the gate selector remains on the 25 contact block 228. Assume then that the despatcher wishes to send car one to the third floor. He presses his button P. b. 3 corresponding to that car. The car starts to move upwardly and the brushes 146 and 30 A travel off from their respective contact blocks and move to the left as indicated by the arrows. This immediately deenergizes the solenoid 156 and its core drops to the position indicated by dotted lines, thus opening a circuit between the blocks P, N, O, and lamp F becomes extinguished. Nothing 35 happens until the car reaches the third floor, where it will stop and the gate will automatically open, revolving "knock-out" 40 K which will extinguish gate lamp I. Lamp H will then light up because solenoid 153 is automatically energized, which immediately closes switch 169 and energizes solenoid 156, thus closing the lamp circuit at 45 the switch P, N, O. The lamps on the control board then have the appearance of that indicated with relation to car 2 in Fig. 7, that is, the car position lamp H is lighted and the gate indicating lamp I is extinguished, showing the despatcher that the 50 car is at the third floor but the gate is open. When the passenger on the car is ready to descend, he presses his "close" button 195 which causes the gate to close and the 55 "knock-out" K to rotate from the position indicated in Fig. 5 until it again reaches the position indicated in Figs. 4 and 6, just as the gate reaches its closed position. The despatcher then sees the lights in the condition indicated with respect to car three 60 on his panel board and knows that all the gates of that shaft are closed and he may then safely send the car to another floor.
- If it were desired to have the lamps F, 65 G and H light up successively as the car
- passes the floors, whether the car stops at any one or not, this could be accomplished by permanently connecting stationary panel blocks P N O, but it is deemed more desirable and in fact, a much safer mode of operation to have the position lamps burns only when the car has reached the floor to which it is intended it shall travel. Where a large number of cars, such as from seven to ten in a bank are operated by a single despatcher, it has been found that it is much safer to arrange the lights in this manner because otherwise the despatcher might become confused if the floor lamps lit up successively and think that a car which was just passing a floor was ready to move from that floor, particularly where he has to keep track of so many elevators. It is therefore deemed much safer to have the position lights burn only when the car is at rest at a 70 floor.
- It is understood that while the foregoing embodiment illustrates the construction now deemed most preferable, the invention under consideration and the claims therein are not limited to the arrangement, mode of operation or constructions above specifically described.
- What is claimed is:
1. In combination, a hatchway, gates 95 along the same and means for operating the gates, an elevator car, a despatcher's station, means thereat whereby a despatcher may cause the car to start from any floor and stop at any other of said floors; and, at 100 said station, signaling means controlled by the gates and indicating when the gate of the floor corresponding to the position of the car is closed, and other signaling means controlled by the car's movement and indicating the car's position.
  2. In combination, a hatchway, gates along the same, and means for operating the gates, an elevator car, a despatcher's station and means thereat whereby a despatcher may cause the car to start from any floor and stop at any other of said floors; and, at 110 said station, signaling means controlled by the gates and indicating only when all the gates are closed, and other signaling means 115 controlled by the car's movement and indicating the car's position, but only when the car has substantially reached the desired floor.
  3. In combination, a hatchway, gates 120 along the same and means for operating the gates, an elevator car, a despatcher's station and means thereat whereby a despatcher may cause the car to start from any floor and stop at any other of said floors; and, at 125 said station, a single signaling device controlled by the gates and indicating when the gate of the floor corresponding to the position of the car is closed, and other signaling means, one for each floor, controlled by 130

the car's movement and indicating the car's position, but only when the car has substantially reached the desired floor.

4. In combination, a hatchway, gates along the same and means for operating the gates, an elevator car, a despatcher's station and means thereat whereby a despatcher may cause the car to start from any floor and automatically stop at any other of said floors and open the gate thereat; and, at said station, signaling means controlled by the gates and indicating when the gate of that floor is closed, and other signaling means controlled by the car's movement and indicating the car's position.

5. In combination, a bank of hatchways and elevators, gates along each hatchway and means for operating the gates, cars in said hatchways, a despatcher's station and means thereat whereby the despatcher may cause any of the cars to start from any floor and automatically stop at any other of said floors; and, at said station, signaling means individual to each elevator and indicating to the despatcher the position of each car and when its gates are closed.

6. In combination, a hatchway, gates along the same and means for operating the gates, an elevator car, signaling means indicating the position of the car and means for operating the same comprising a selector moved correspondingly with the car, and means preventing the operation of said signaling means except when the car is substantially at the floor at which it is to stop.

7. In combination, a hatchway, gates along the same and means for operating the gates, an elevator car, a car position indicator at a central point and means for operating the same comprising a selector moved correspondingly with the car, and means rendering the position indicator inoperative to indicate the car's position except when the car arrives at a floor and its gate-opening mechanism has started to function.

8. In combination, a bank of hatchways

and elevators, gates along each hatchway and means for operating the gates, cars in said hatchways, a despatcher's station and means thereat whereby the despatcher may cause any of the cars to start from any floor and automatically stop at any other of said floors; and, at said station, signaling means individual to each elevator and indicating to the despatcher the position of each car and when its gates are closed and comprising for each car a visible signal displayed only when all its gates are closed, and a position indicator controlled in part by the movement of its car and in part by the gate-operating mechanism.

9. In combination, an elevator car and hatchway and gates along the same, an electric circuit and a gate indicating signal operated by the circuit, and means controlling the circuit and comprising a switch common to all the gates and operated by each gate independently, whereby the signal is given only when all the gates are closed.

10. In combination, a bank of hatchways and elevators, gates along each hatchway, cars in said hatchways and a despatcher's station; and at said station signaling means grouped together and individual to each elevator and indicating to the despatcher the position of each car and when its gates are closed, and comprising for each car a visible signal displayed only when its gates are closed and controlled independently by each gate of that car, and a position indicator controlled in part by the movement of its car and in part by the gate-operating mechanism and comprising a signal which is given only when the car is substantially at the floor at which it is to stop.

Dated New York, N. Y., this 15th day of April, 1921.
